TUBULAR CLEAT WRENCH WITH CIRCUMFERENTIALLY SPACED GRIPPING TEETH

Clyde C. Manchester, Stryker, Ohio

Application June 27, 1951, Serial No. 233,837

2 Claims. (Cl. 81—90)

1

This invention relates to improvements in cleat wrenches, that is to say wrenches for tightening or loosening shoe cleats such as are commonly used on shoes worn by contestants in athletic games.

One of the objects of the invention is the provision of a wrench that is adapted to grip and turn a cleat of frusto-conical shape, the tapered wall of which is smooth and difficult to grasp tightly.

Another object is the provision of a wrench of the character stated which shall be light in weight and of relatively small size and hence well adapted to be carried in the pocket of the owner.

Still another object is the provision of a wrench of the character stated which shall be easy and convenient to use and which shall be well adapted for rapid manipulation.

Other objects and features of novelty will appear as I proceed with the description of those embodiments of the invention which, for the purposes of the present application, I have illustrated in the accompanying drawing, in which

Fig. 1 is a perspective view of a football shoe with conventional cleats, showing my wrench in operative engagement with one of the cleats.

Fig. 2 is an elevational view, partly in section of the wrench in position to be forced into gripping engagement with a cleat.

Fig. 3 is a cross-sectional view taken substantially on the line 3—3 of Fig. 2.

Fig. 4 is an end view looking in the direction of arrow 4, Fig. 2.

Fig. 5 is an elevational view of a modification, and

Fig. 6 is an end view of the same.

In the drawing the sole of a football shoe is indicated at 10. A series of recesses are formed in the sole extending upwardly from the lower surface thereof, and in these recesses are mounted a like number of metal inserts 11. Each of these inserts is provided with a threaded socket in which is mounted a stud 12. An integral hexagonal shaped collar 13 is formed on the stud intermediate its ends in order to provide a convenient means for setting or removing the stud. A considerable portion of the stud 12 projects outwardly beyond the collar 13 to form a post upon which the cleat is to be mounted.

These conical cleats 15 are supplied in different sizes. In general, when the playing field is dry relatively small cleats may be preferred, whereas larger cleats are preferable when the ground is muddy and slippery and it is difficult

2

to obtain a good foothold. Sometimes changes in weather conditions make it highly desirable for a player to be able to change cleats rapidly, as in the rest period between halves of a football game. Each cleat is formed with a central cavity to receive a steel sleeve 16 that is internally threaded to screw onto the projecting part of the stud 12. If the cleat is formed of rubber or rubber composition, the sleeve 16 may be vulcanized to it. If the cleat is made of aluminum or other material the sleeve is secured to it by other suitable means.

The wrench comprises a tubular handle 18 having an outer diameter of the order of one ¹⁵ inch, which has been found to be a satisfactory size to fit the hand of the average man and enable him to exert the required turning force. Preferably the outer surface of the handle is knurled as shown. Aluminum tubing is excellent as the handle material, since it is light in weight and easily worked.

On the ends of this tube are mounted caps ¹⁹ and ²⁰ which are preferably steel stampings. Both caps have cylindrical skirts which fit snugly ²⁵ over the ends of the tubing. The flat end portion of cap ¹⁹ is cut out centrally to provide a hole of a size to fit over the small end of a cleat and extend part way up its side, the distance depending upon the size of the cleat in question. ³⁰ The opening in the flat part of the cap is symmetrical with the axis of the handle so as to center the tubular handle 18 on the cleat. The opening is so formed that a series of prongs ²¹ evenly spaced around the opening project inwardly beyond the other edges thereof. The cap is preferably casehardened, and when so hardened a single such prong is effective, but I prefer to employ three or more prongs so that the tool may set squarely upon the cleat and so ³⁵ that the grip may be properly distributed around it.

The cap ²⁰ at the opposite end of handle 18 is preferably formed with a central equilateral opening ²³ of a shape and size to enable the cap to function as a socket wrench. In the illustrated case the opening is proportioned to fit hexagonal collar ¹³, so that in case there is a breakage of the stud ¹² it may be readily removed and a new one fastened in place.

In order to prevent the caps ¹⁹ and ²⁰ from turning relative to the handle, indentations ²⁴ may be formed to lock the caps to the handle tube.

In the modification of Figs. 5 and 6 the entire ⁵⁵ tool is made of a single piece of steel tubing, a

3

portion of which is knurled to provide a firm grip for the user. One end of the tube may be crimped inwardly at an angle of about 45° as shown at 29 to provide a rounded end for enabling the operator to apply pressure with his hand comfortably.

The first step in forming the opposite or operating end of the tool may be somewhat the same, that is it may be crimped inwardly in a die at an angle of approximately 45°. The second step is to flatten the crimped end in another press to bring the metal of that end into a plane at right angles to the tube proper. Finally a portion of this inwardly bent metal is cut away by a suitable die to leave a plurality of evenly spaced prongs or teeth 30. The end including the prongs may then be hardened.

The operation and use of my improved wrench will be obvious from the foregoing description 20 of its construction. The wrench is small and sturdy, can exert ample torsional effort. It is especially convenient because of its light weight, and its generally smooth circular contours leave 25 no projections to cause possible injury to the user or to catch in his clothing when carried in a pocket.

Having thus described my invention, I claim:

1. A wrench for shoe cleats of truncated cone shape, comprising a tubular sheet metal handle 30 of a diameter greater than the minimum diam-

5

4

eter of the cleat, one end of the handle having an inwardly directed annular flange adapted to engage the tapered wall of the cleat intermediate its ends, said flange having a sharp hard point adapted to be embedded slightly in the cleat and to impart rotational effort thereto when the handle is turned about its axis.

2. A wrench for shoe cleats of truncated cone shape, comprising a tubular sheet metal handle of a diameter greater than the minimum diameter of the cleat, one end of the handle having an inwardly directed annular flange, and said flange having a series of hard metal evenly spaced prongs each projecting inwardly therefrom a like distance, said prongs being adapted to center the handle with respect to said cleat and to grip it and impart rotational effort thereto when the handle is turned about its axis.

CLYDE C. MANCHESTER.
